UNITED STATES PATENT OFFICE

ERIK W. DAUBLE, OF DETROIT, MICHIGAN

DOORSTOP

Application filed February 2, 1932. Serial No. 590,430.

This invention relates to improvements in door stops, and refers more particularly to door stops intended to hold hinged doors when in open position.

3 It is an object of the invention to provide a door stop consisting of a plate adapted to be secured to one side of a door and having spaced forwardly projecting portions intermediately of its height between which and 10 the adjacent face of the door a trunnion is so supported that it may both be turned about its axis and moved substantially at right angles thereto; and to form spaced extensions on the plate which project upwardly adjacent 15 the door behind the lower extremities of the outwardly flexed projections to engage corresponding flat faces formed on the trunnion extremities so that the said trunnion may only drop to the bottom of the bearing formed 20 between the forwardly projecting plate portions and the adjacent face of the door when it has been turned to a given position; and to provide a holding member which projects from the trunnion between the said outwardly 25 projecting plate portions. Thus I aim to provide means for retaining the trunnion against accidental rotation when the holding member has been turned to an upwardly directed position in which it is placed when not 30 in use.

Another object of the invention is to provide such a door stop wherein the spacing both between the flat faces on the trunnion and that between the extensions which engage the flat faces is greater than the spacing between the forwardly flexed bearing portions so that at all angular positions of the trunnion a portion thereof will lie adjacent the forwardly flexed bearing portions, thus preventing undue play of the trunnion when it lies in the upper bearing portion.

A further object of the invention is to provide a door stop wherein the holding member is pivotally mounted on a plate in such a manner that it is permitted limited movement at right angles to its axis, and to provide a catch on the member which cooperates with a recess formed in the plate so 50 that the said member may be positively held

in an upwardly directed position when not in use.

With these and other objects and advantages in view which will become apparent as the specification proceeds, the invention is 55 hereinafter more fully described with the aid of the accompanying drawing, in which:

Figure 1 illustrates a front elevation of the invention applied to a door.

Figure 2 is a side view thereof with the holding member in operating position.

Figure 3 is a view similar to that shown in Figure 2 except that the holding member is supported in an upwardly directed position, and

Figure 4 is a fragmentary view of a portion of the plate when detached from the door.

Referring to the drawing, 1 designates a plate which is attached to one side of a door A as by screws 2, and intermediately of its height the said plate is outwardly flexed at 3. Integral with the plate and projecting upwardly therefrom adjacent the face of the door A from the lower extremity of the outwardly flexed portion 3 is a plate extension 4. The outwardly flexed portion 3 is vertically slotted at 3a to form two spaced and vertically elongated bearings 5 between it and the door A. The plate extension 4 is also 80 vertically slotted from its upper margin as shown at 6, and the width of the slot 6 is greater than that of the slot 3a for a reason that will hereinafter become apparent. 7 denotes a wall formed by the plate 1 and extending completely across the latter between the lower extremities of the slots 3a and 6 and separating the latter.

In the bearings 5 a trunnion 8 is so mounted that it may rotate about its axis or move substantially at right angles thereto. Extending radially from the trunnion 8 through the slot 3a is a holding member 9, the inner extremity of which is preferably a driving fit into an aperture 10 formed in the said trunnion. The wall 7, which constitutes the lower extremity of the slot 3a forms a stop to limit the downward swing of the member 9 so that it cannot assume too vertical a position

in which its holding effect would be materially lessened.

The trunnion 8 is circular in cross section and has portions cut therefrom towards its 5 extremities thereby forming aligned flat faces 11 thereon. These flat faces are so disposed relative to the member 9 that when the latter is upwardly directed, as shown in Figure 3, they lie substantially parallel with 10 the extension 4 so that the trunnion 8 may then drop between the said extension and the outwardly flexed plate portion 3, and with the completely circular central portion of the 15 said trunnion resting partly in the extension slot 7. The axial length of the completely circular central trunnion portion is somewhat greater than the width of the slot 3a so that when the member 9 and trunnion 8 assume the position shown in Figures 1 and 20 2 portions of the completely circular trunnion portion rest against both bearings 5 and prevent the excessive play which the trunnion would otherwise be permitted.

Substantially centrally of the width of the 25 plate 1 and above the flexed portion 3 is another forwardly flexed plate portion 14 which forms a recess between its inner face and the door A. At the top of this flexed plate portion and extending downwardly for a portion 30 of its height an opening 16 is formed therethrough. On the holding member 9 is a projection, which is preferably wedge-shaped, and extends substantially parallel with the said member. This projection may 35 be secured to the member 9 in any desired manner, in the present instance a pin 18 is formed integral with the said projection and extends through an opening 19 formed in the member 9.

40 When the holding member 9 is in its down-turned operating position the trunnion 8 is forced upward by the ground indicated at B, thus lifting the trunnion in its bearings so that it contacts the tops of the latter. When 45 the door A is closed and the member 9 not in use the trunnion 8 is turned so that the member projects upwardly. When the flat faces 11 of the trunnion 8 are parallel with the extension 4 and in alignment with the outer 50 face of the latter the trunnion 8 drops into the lower portions of the bearings 5 and then the projection 17 enters the plate opening 16 and passes into the recess 15. The holding member 9 is then retained in its upward position until it is lifted so that its projection 17 55 is released from the recess 15 and the flat trunnion faces 11 are raised above the plate extension 4.

60 While in the foregoing the preferred embodiment of the invention has been described and shown, it is understood that the construction is susceptible to such alterations and modifications as fall within the scope of the 65 appended claims.

What I claim as my invention and desire to secure by Letters Patent is:

1. A door stop comprising a plate adapted to be secured to one side of a door, said plate having a forwardly flexed portion intermediately of its height, said forwardly flexed portion being vertically slotted so as to form two spaced and vertically elongated bearings between said flexed portions and said door, a plate extension in alignment with the plate extremities and projecting upwardly from the bottom of said forwardly flexed portion, a trunnion rotatable in said bearings, and a holding member extending from said trunnion between said spaced bearings, said plate extension being vertically slotted from its upper extremity, said trunnion having a substantially circular centre portion and aligned flat faces formed at its extremities, said central circular portion of the trunnion being adapted to lie in the plate extension slot and the flat faces at the trunnion extremities being adapted to rest in front of the plate extension thereby holding said trunnion against rotation when positioned in front of said plate extension.

2. A door stop comprising a plate adapted to be secured to one side of a door, said plate having a forwardly flexed portion intermediately of its height which is vertically slotted to form two spaced and vertically elongated bearings between said plate and said door, a trunnion rotatable in said bearings and permitted vertical movement therein, said trunnion having aligned flat faces adjacent its extremities opposite said outwardly flexed portions, and projections extending from said plate into said bearings adjacent said door between which and said flexed portions said trunnion is adapted to enter and be held against rotation when it is so turned that its flat faces are vertical, and a holding member extending substantially radially from said trunnion.

3. A door stop consisting of a plate adapted to be secured to one side of a door, said plate having a forwardly flexed portion intermediately of its height, said forwardly flexed portion being vertically slotted to form two spaced and vertically elongated bearings between said door and said flexed portion, a plate extension in alignment with said plate extremities projecting upwardly adjacent the door from the bottom of said forwardly flexed portion and behind said forwardly flexed portions, a trunnion rotatable in said bearings, a holding member extending substantially radially from said trunnion between said bearings, said trunnion having aligned flat faces formed in its periphery adjacent its extremities, said trunnion, when it is so turned that said faces are vertical, dropping between said plate extension and the forwardly flexed portion to the bottom of the bearings and being then held against ro-

tation, and a stop formed at the lower extremity of the slot which separates the bearings, said stop being adapted to limit the downward inclination of said holding member.

4. A door stop comprising a plate adapted to be secured to one side of a door, said plate having a forwardly flexed portion intermediate of its height, said forwardly flexed portion being vertically slotted to form two spaced and vertically elongated bearings between said plate and said door, a trunnion rotatable in said bearings and permitted vertical movement therein, said trunnion having aligned flat faces adjacent its extremities opposite said flexed bearing portions, and having its central portion substantially circular in section, said circular central trunnion portion being wider than the spacing between said forwardly flexed bearing portions so that as said trunnion rotates it is supported at all angular positions against horizontal movement in the bearings, and a bifurcated projection extending from said plate into said bearings adjacent said door between which and said forwardly flexed bearing portions said trunnion is adapted to enter and be held against rotation when it is so turned that its flat faces are substantially vertical, said bifurcations being spaced further apart than said forwardly flexed bearing portions to permit the extremities of the central circular trunnion portion to rotate behind said flexed portions.
